Patented Nov. 4, 1919.

INVENTOR.

*Homer J. Young,
BY Leonard A. Smith,
His ATTORNEY.*

UNITED STATES PATENT OFFICE.

HOMER J. YOUNG, OF DAYTON, OHIO.

DESIGN FOR A SEPARATOR-CASING.

54,116.

Specification for Design.

Patented Nov. 4, 1919.

Application filed January 14, 1919. Serial No. 271,153. Term of patent 14 years.

To all whom it may concern:

Be it known that I, HOMER J. YOUNG, a citizen of the United States, residing at Dayton, in the county of Montgomery and State of Ohio, have invented a new, original, and ornamental Design for a Separator-Casing, of which the following is a specification, reference being had to the accompanying drawing, forming part thereof.

The figure is a perspective view of the separator casing, showing my new design.

I claim:

The ornamental design for a separator casing, as shown.

HOMER J. YOUNG.

Witnesses:

HOWARD S. SMITH,

WILLIAM B. HOUNELL.
